W. H. EDWARDS.

EXPANSIBLE AND CONTRACTABLE LEAF BINDER AND COVERING MEMBER THEREFOR.
APPLICATION FILED FEB. 18, 1921.

1,406,829.

Patented Feb. 14, 1922.

Inventor:
William H. Edwards
by Cyrus W. Rice
his Attorney.

UNITED STATES PATENT OFFICE.

WILLIAM H. EDWARDS, OF GRAND RAPIDS, MICHIGAN.

EXPANSIBLE AND CONTRACTABLE LEAF BINDER AND COVERING MEMBER THEREFOR.

1,406,829.

Specification of Letters Patent. Patented Feb. 14, 1922.

Application filed February 18, 1921. Serial No. 446,033.

To all whom it may concern:

Be it known that I, WILLIAM H. EDWARDS, a citizen of the United States, residing at Grand Rapids, in the county of Kent and

5 State of Michigan, have invented new and useful Improvements in Expansible and Contractable Leaf Binders and Covering Members Therefor, of which the following is a specification.

10 The present invention relates to expansible and contractable leaf-binders and covering members therefor, and its object is to provide such a device which as an entirety may be readily adapted to greater or less thicknesses 15 of the body of leaves held thereby; and further, to provide such a device improved in various respects hereinafter appearing.

This object is attained by, and the invention finds preferable embodiment in, the 20 structure hereinafter particularly described and illustrated by the accompanying drawings, in which:—

Figure 1 is an endwise view of the opened device, partially sectioned on line 1—1 of 25 Figure 2; and

Figure 2 is an inside view or top plan view of the same in the position shown in Figure 1.

In the embodiment of the invention chosen 30 for illustration by the drawings and for detailed description in the body of this specification, the leaves composing the leaf body 1 are held in the device by flexible binding means, as the bands 2 extending through

35 the usual slots or notches in the binding edge of the leaves, said binding means being carried by the oppositely disposed covers 3, 4 of the expansible and contractable leaf-binder, designated generally 5. Means for

40 securing the bands in a position to accommodate and properly hold the leaf body are carried by one or both of the covers, such securing means being in the construction illustrated the clamping elements 6 pivotally

45 mounted at 7 on the covers and having the cam portions 8 adapted to clamp the bands to the covers and to release the same by turning the arms 9 of said elements. Any suitable securing means or band adjusting and

50 securing means may however be adopted to hold the bands in desired adjustment, and the bands may be anchored at one end on one cover and the securing means may be carried by the other cover only. In the

55 construction illustrated these bands pass through the guides 30 on the covers and

through the binding strips 10 on either side of the leaf body and having fly leaf extensions 11, the free ends of the bands being connected by cross bars 12. 60

One of the covers 3 has a sheath or opening 13, open toward the other cover 4, and said other cover 4 has a flexible extension or sheet portion 14 contained in and slidably in said sheath 13. A covering member 15 65 adapted to lie outside and adjacent to the cover 4 in the closed position of the device, has a flexible extension 16 connected to the flexible extension 14 at 17 and slidably therewith in the sheath 13. When the covers 3, 70 4 are adjusted to the thickness of the leaf body, the flexible extensions 14, 16 are slid in the sheath to a position registering with the thickness of the leaf body between and held by the covers, and as the device is 75 opened and closed these flexible extensions 14, 16 are flexed with the bands 2.

The covering member 15 may have at its free end flexible means, as the strap 19 for detachably connecting the same with the free 80 end of the cover 3 as by passing through the loop 20 on the outside of said cover; and a flexible strap 21 on the outer side of the cover 3 and the outer side of the covering member 15 and slidably connected to 85 at least one of them, as by passing through the guides 22, may also be provided, for more securely holding the device closed or for carrying the same.

Any type of means for holding the leaves 90 and for adjusting the covers thereto may be adopted in the broader aspects of this invention.

The invention being intended to be pointed out in the claims, is not to be limited to or 95 by details of construction of the particular embodiment thereof illustrated by the drawings or hereinbefore described.

I claim:

1. In a device of the character described; 100 an expansible and contractable leaf-binder having oppositely disposed covers one of which has a sheath opening toward the other cover and said other cover having a flexible extension slidable in the sheath; a covering 105 member having a flexible extension connected to the first-mentioned slidable extension and slidable within the sheath.

2. In a device of the character described; 110 an expansible and contractable leaf-binder having flexible binding means extending through the leaves held therein and means

- for securing said binding means in adjusted position, and having oppositely disposed covers carrying said binding means and adjusting means, one of said covers having
- 5 a sheath opening toward the other cover and said other cover having a flexible extension slidable in the sheath; a covering member having a flexible extension connected to the first-mentioned extension.
- 10 3. In a device of the character described; an expansible and contractable leaf-binder having oppositely disposed covers one of which has a sheath opening toward the other cover and said other cover having a flexible
- 15 extension slidable in the sheath; a covering member having a flexible extension connected to the first-mentioned slidable extension; flexible means for detachably connecting the free end of the covering member with
- 20 the free end of the first-mentioned cover.
4. In a device of the character described; an expansible and contractable leaf-binder having oppositely disposed covers one of which has a sheath opening toward the other cover and said other cover having a flexible 25 extension slidable in the sheath; a covering member having a flexible extension connected to the first-mentioned slidable extension; flexible means for detachably connecting the free end of the covering member with the free end of the first-mentioned cover; a flexible strap on the outer side of the first-mentioned cover and on the outer side of the covering member and slidably connected to at least one of them. 30
- 35

In testimony whereof I have hereunto set my hand at Grand Rapids, Michigan, this 14th day of February, 1921.

WILLIAM H. EDWARDS.
